Attest.

UNITED STATES PATENT OFFICE

RICHARD S. BROGIE, OF CHICAGO, ILLINOIS, ASSIGNOR TO BROGIE WINDOW CORPORATION, OF CHICAGO, ILLINOIS, A CORPORATION OF ILLINOIS

WINDOW CONSTRUCTION

Application filed April 29, 1928. Serial No. 359,107.

This invention belongs to the general type of windows wherein one sash slidably moves in contact with or in proximity to a cooperating sash. It is a companion case with one heretofore filed by me pertinent to improvements in windows in which the sashes are pivotally supported and swung on the pivot as an axis.

In the drawings, Fig. 1 is a front elevation of a window of well known type in which the sashes 1-1 move one upon the other;

Fig. 2 is a transverse section on the line 2-2 of Fig. 1;

Fig. 3 is a central vertical section on the line 3-3 of Fig. 1;

Fig. 4 is a section line 4-4 of Fig. 3, showing the weight connections, a fraction of the sash and a form of spring which may be employed in the device; and

Fig. 5 is a section on the line 5-5 of Fig. 1 showing a section through the lower part of the sash and sill.

Referring to Fig. 1, the sashes 1-1 are contained in a frame provided with jambs 25 of the usual type. As shown, the sash on each side preferably extends the vertical side of the sash, and as at 2-2 is constructed with a box-like end 3 which, as shown, is provided with a telescoping part 4 adapted 30 to slide in the box 3. Suitable springs 5 extending between the outer end of the telescoping part 4 and the base 6 of the box normally hold the telescoping member to its outer limit of movement. 7 indicates the 35 jamb of the window frame against which the telescoping part 4 is forced by the spring, insuring a snug and close fit between the two parts excluding air and dust.

In the preferred form, the jamb and its 40 telescoping part 4 have their meeting faces formed to cooperate as stated. As shown, the jamb 7 is beveled while the faces of the telescoping part 4 is provided with a reverse bevel so that the two fit together 45 snugly. Any preferred form of contour may be adopted, however.

Referring to Fig. 4, 8 indicates the weight 50 pulley attached to a clip 9 which is secured to the top of the sash. 5 is a spring vertically arranged within the box 3 tending to hold

the telescoping parts 4 to their outer limit of movement, as stated. Any preferred type of spring or resilient means may be employed.

Carrying out the idea for excluding wind and dust, Fig. 3 shows the top part or rail 55 of a window preferably equipped with a box 11 having its top edge formed to cooperate with the top jamb 12. The bottom rail 13 may be similarly constructed, cooperating with the window sill 14.

As shown the improvement is particularly adapted for use with metal windows. It is obvious, however, that it is equally adapted for use with wooden sash, those skilled in the art readily making such slight modifications 60 as may be required.

Having thus described my invention, it is obvious that various immaterial modifications may be made in the same without departing from the spirit of my invention; 70 hence, I do not wish to be understood as limiting myself to the exact form, construction, arrangement, and combination of parts herein shown and described or uses mentioned.

What I claim as new and desire to secure by 75 Letters Patent is:

1. A window structure comprising sliding sash members provided with a recess formed in the longitudinal edges thereof, in combination with laterally movable members slidably mounted in and closely fitting said recesses, a plurality of relatively flat V-shaped strips of material each having its apex fastened to the sash member and its ends fastened to said 80 slideable member to provide resilient means arranged to force said slideable members toward their outer limit of movement with the adjacent faces of the slideable member and the window jamb in cooperating relation, one of said faces having a convex bevel and 85 the other a concave bevel.

2. A window structure comprising sliding sash members provided with a recess formed in the longitudinal edges thereof, in combination with laterally movable members slidably mounted in and closely fitting said recesses, a plurality of relatively flat V-shaped strips of material each having its apex fastened to the sash member and its ends fastened to said slideable member to provide resil- 90 95 100

ient means arranged to force said slidable members toward their outer limit of movement with the adjacent faces of the slidable member and the window jamb in cooperating relation, the cooperating faces of said members being convexly beveled and of the jamb being concavely beveled.

In witness whereof I hereunto subscribe my name this 26th day of April, A. D., 1929.
